attty.

UNITED STATES PATENT OFFICE.

JOHN H. KUHNS, OF WILKINSBURG, PENNSYLVANIA, ASSIGNOR, BY MESNE ASSIGNMENTS, TO HI-VOLTAGE EQUIPMENT COMPANY, A CORPORATION OF PENNSYLVANIA.

SWITCH.

1,373,008.

Specification of Letters Patent.

Patented Mar. 29, 1921.

Application filed October 17, 1919. Serial No. 331,356.

To all whom it may concern:

Be it known that I, JOHN H. KUHNS, a citizen of the United States, and a resident of Wilkinsburg, in the county of Allegheny and State of Pennsylvania, have made a new and useful Invention in Switches, of which the following is a specification.

The invention relates to electric switches, and particularly to those for high tension currents known as "horn gap switches." The invention has for some of its more important objects; the provision of a switch construction wherein the mechanical means for swinging the switch bar are simplified and improved; the provision of a switch construction which may be cheaply constructed and which is not liable to get out of order; the provision of a horn gap switch in which one of the horns ordinarily used may be dispensed with to advantage; and the provision of a switch having improved contact means for the switch bar and in which the contact will not be rendered ineffective by reason of sleet or snow. One embodiment of the invention is illustrated in the accompanying drawings wherein;

Figure 1 is a side elevation of the apparatus, the dotted lines showing the switch bar in open position. Fig. 2 is a plan view 30 of the apparatus with the housing over the switch contacts removed. And Fig. 3 is a detail on an enlarged scale of the end of the contact bar.

Referring first to the general arrangement of parts, 1 is a base upon which are mounted the metal insulator rods, 2 and 3, and the crank rod 4; 5 is a crank carried by the upper end of the crank rod and provided with an upwardly extending crank pin 6 at its free end; 7, 8 and 9 are insulators mounted respectively on the bars 2 and 3 and crank pin 6, such insulators being of the well known type commonly employed in connection with high tension currents; 10 is a bracket mounted upon the insulator 7; 11 is a switch bar pivoted in the bracket 10 at 12 and having a crank arm 13; 14 is a contact plate mounted upon insulator 8 and provided with contact means with which the bar 11 is adapted to co-act when the bar is in its horizontal position; and 15 is a housing mounted upon the contact plate and carrying an upwardly and laterally extending horn 16.

The insulator 9 carries a metal cap 17 which cap is provided with a pair of upstanding lugs 18 and 19. A stud bearing pin 20 is screwed into the lug 18 and a connecting rod 21 is pivotally connected to this pin at one end and to the crank end of the switch bar at its other end. The connections between the connecting rod 21 and the pin 20 and crank end 13 are relatively loose so that there is no binding at the connections when the crank arm 5 is turned to operate the switch bar. The pin 20 is in substantial alinement with the crank pin 6, while the center line of the lug 19 is in substantial alinement with the center line of the crank rod 4. The lug 19 is connected 70 with a lug 22 on the bracket 10 by means of a steady rod 23. The lug 19 thus provides a second bearing for the crank 5 and the insulator 9 carried thereby.

The crank rod 4 may be provided at its lower end with a crank and operated by any suitable mechanism in the usual way and a second crank arm 24 preferably integral with the arm 5 serves as a means for connecting this apparatus with another similar apparatus or with a series of such apparatuses.

The switch bar 11 is provided with a movable end 25 pivoted to the bar at 26 and also having a wire connection 27 for carrying the current across the joint. When the bar is in its lower position as illustrated in full lines, the end 25 is in alinement with the main portion of the bar but when the bar is raised as indicated in dotted lines the end 25 assumes the position illustrated. The end 25 preferably consists of the tapering side members shown in Figs. 2 and 3 secured together by means of a nose piece 28, such nose piece being held in position by means of the countersunk screws 29 so that such nose piece may be readily replaced. A stop pin 26^a on the bar 11 engages the lug 26^b on the part 25, and prevents the joint breaking downward below the position shown in Fig. 1.

The contact plate 14 is provided with a pair of upstanding plates or lugs 30 in which are slidably mounted pairs of pins 31, such pins carrying at their forward ends the contact plates 32. The plates are yieldingly held in forward position by means of coil springs 33 mounted on the pins 31. The

plates are connected to the lead 34, while the bracket 10 on the insulator 7 is connected to the other lead 35. A housing 15 lies above the contacts on the plate 14, such housing 5 being removably secured to the plate 14 and serving to protect the contacts from snow and sleet.

In the operation of closing the switch the crank rod 4 is turned swinging the crank 5 and causing the switch bar 11 to move down from the dotted line position. The inclined switch end 25 first engages the upper surface of the contact plate 14 and as the switch bar descends still further this end slides 15 along the plate which acts as a guide surface and between the contact plates 32 until the parts reach the position indicated in Figs. 1 and 2, at which time the end 25 is in alignment with the bar 11 and the contact surfaces are in full engagement.

On the reverse movement of the operating crank 5, the raising of the switch bar 11 causes the switch end 25 to be turned at an angle to the body of the bar and dragged 25 free from the contact plates 32. At this time, as the end 25 leaves the plate 14 an arc is set up between the switch end and the housing 15 and the arc continues between the end and the horn 16 as the bar rises. 30 The arc works upward and is broken between the switch bar end 25 and the horn 16. As the arc extends from the nose piece 28 to the horn 16, such nose piece is the part worn away and this part may be readily replaced 35 when it becomes necessary. In closing the switch, the heat incident to arcing serves to clear the contacts of any snow or sleet which may have collected while the switch was open. The contact arrangement just described insures a relatively perfect engagement between the contacting surfaces because of the sliding engagement and the inclined yielding plates.

The switch construction is relatively cheap 45 and not liable to get out of order. The insulators employed are of standard construction and the wearing parts are inexpensive and easily replaced. The crank arrangement with the connection 20 at the center of the 50 insulator imposes no twisting strain upon the insulator tending to loosen or break the insulator such as is the case where the insulator itself constitutes a crank with its connection off center with respect to the center 55 of the insulator. The wear upon the bearing of the crank 5 is reduced to a minimum by the use of the steady bar 23 which further reduces the strain upon the insulator 9. The arrangement involving the use of the switch 60 bar end 25 not only insures a satisfactory contact when the switch bar is closed but also eliminates the requirement for a second horn such as is often carried by the switch bar although the switch bar may be provided with a horn if so desired. Other ad-

vantages incident to the construction will be readily apparent to those skilled in the art.

What I claim is:

1. In combination in a switch, an insulator provided with contact means, a second insulator, a switch bar having a crank end and pivoted on the second insulator and adapted to make contact at its free end with said contact means, a crank adjacent the first insulator movable in a plane transverse to the 75 plane of movement of the switch bar and having a crank pin at its end, a third insulator mounted upon said crank pin, and a connection between the crank end of the switch bar and said third insulator. 80

2. In combination in a switch bar, an insulator provided with contact means, a second insulator, a switch bar having a crank end and pivoted on the second insulator and adapted to make contact at its free end with 85 said contact means, an insulated crank member located intermediate the two insulators movable in a plane transverse to the plane of movement of the switch bar, and a connecting rod pivoted at one end to the 90 crank end of the switch bar and at its other end to said crank member.

3. In combination in a switch, an insulator provided with contact means, a second insulator, a switch bar having a crank end and pivoted on the second insulator and adapted to make contact at its free end with said contact means, a crank located intermediate the two insulators movable in a plane transverse to the plane of movement of the switch 100 bar and having a crank pin at its end, a third insulator mounted upon said crank pin, and a connection between the crank end of the switch bar and said third insulator. 105

4. In combination in a switch, an insulator provided with contact means, a second insulator, a switch bar having a crank end pivoted at one end for movement upon said second insulator and adapted to make contact at its free end with said contact means, 110 a crank movable in a plane transverse to the plane of movement of the switch bar, and having an upright crank pin at its free end, a third insulator mounted upon said crank pin, a connection extending laterally from the crank end of the switch bar and pivoted on the third insulator at a point in alignment with said crank pin, and a steady bar secured at one end to said second insulator, and pivoted at the other end upon the third 115 insulator at a point in vertical alignment with the axis of rotation of said crank upon which the third insulator is mounted. 120

5. In combination in a switch, an insulator provided with a pair of opposing extending contact members mounted above a guide surface, a second insulator, a switch bar pivoted at one end thereon for movement toward and from the first insulator, and a contact end pivoted for movement in the 125 130

plane of movement of the switch bar on the free end of such bar and having contact surfaces at its sides, the said end being adapted when moved to closed position to engage the 5 said guide surface, and then slide between the opposing contact members as the bar approaches its final position and the said contact end is brought toward alinement with the switch bar.

10 6. In combination in a switch, an insulator provided with a pair of opposing contact members inclined toward each other, a guide surface on the insulator below the contact members, a second insulator, a switch bar 15 pivoted at one end thereon for movement toward and from the first insulator, and a contact end pivoted for movement in the plane of movement of the switch bar on the free end of such bar, and having contact 20 surfaces at its sides inclined toward each other, the said end being adapted when moved to closed position to engage the said guide surface and then slide between the opposing contact members as the bar approaches 25 its final position and the said con-

tact end is brought toward alinement with the switch bar.

7. In combination in a switch, an insulator provided with a pair of opposing contact members inclined toward each other, a guide 30 surface on the insulator below the contact members, a second insulator, a switch bar pivoted at one end thereon for movement toward and from the first insulator, and a contact end pivoted for movement in the 35 plane of movement of the switch bar on the free end of the switch bar, and comprising a pair of side contact members inclined toward each other and a removable wear block secured between the forward ends of 40 said members, the said end being adapted when lowered to engage said guide surface and then slide between the first mentioned contact members as the bar approaches its lower position and the said end approaches 45 alinement with the switch bar.

In testimony whereof, I have hereunto subscribed my name this 16th day of October, 1919.

JOHN H. KUHNS.
